UNITED STATES PATENT OFFICE.

LESLIE HOLMES GARLINGHOUSE, OF ASPINWALL, PENNSYLVANIA, ASSIGNOR TO
BLAW-KNOX COMPANY, A CORPORATION OF NEW JERSEY.

SHORE.

Application filed April 19, 1920. Serial No. 374,825.

To all whom it may concern:

Be it known that I, LESLIE HOLMES GARLINGHOUSE, a citizen of the United States, residing at Aspinwall, in the county of Allegheny and State of Pennsylvania, have invented certain new and useful Improvements in Shores, of which the following is a specification.

This invention relates to shores and similar false work members, useful, for example, in supporting forms for concrete work.

One of the primary objects of my invention is the provision of improved apparatus of this character whereby I am not only enabled to cut down the amount of supporting structure and, therefore, reduce the carpentry work required, but also to readily compensate for the differences in dimension which are always present in the rough lumber used for such purposes, ensuring the support of the form parts at the proper level.

Still another object of my invention consists in the provision of apparatus of the characteristics specified which is so constructed that the taking down of the forms is greatly facilitated.

The foregoing, together with such other objects as may hereinafter appear, or are incident to my invention, I obtain by means of a construction which I have illustrated in preferred form in the accompanying drawings, wherein:

Fig. 1 is a perspective view illustrating the application of my improvements in the erection of a concrete floor with forms such as shown in my copending application, Serial No. 373,999, filed April 15, 1920; and Fig. 2 is a perspective of one of the shores shown in Fig. 1, drawn on an enlarged scale to more clearly illustrate the parts thereof.

My invention will be best understood from a brief description of a portion of the floor system as shown in Fig. 1. The shores 7 are preferably arranged in rows providing bays A, B, C, etc. The shores are tied and braced in any preferred manner as by the bracing 8 of temporary character. Pairs of ledgers 9 and 10 are supported in a manner to be hereinafter described on the shores

and extend transversely of the bay or bays, the ledgers being of any desired length. The ledgers support form sections such as 55 the panels or pans 11, which may or may not be secured to their respective ledgers. What I term permanent panels 12 cooperate with the panels 11 to constitute the floor form and these are supported directly on 60 top of the shores 7 so as to be independent of the other panels. The panels 12 are also supported at their edge portions by the ledgers. Their construction is shown and described in the aforesaid copending application. 65

In general, the method of operation is as follows: The forms are set up, as set forth, the concrete is poured, and a relatively short time thereafter the ledgers are detached and 70 dropped and with them the panels 11, the permanent panels 12 being left in position to support the concrete until it has thoroughly set. The ledgers and panels 11 are then set up at a new point of use and the work is thus 75 carried out progressively. If ledgers of short length are employed, they and the panels directly supported thereby, may be taken down in units and shifted and set up as such, in which case the panels are preferably de- 80 attachably secured to the ledgers.

Referring now to Fig. 2, it will be seen that each of the shores 7 consists of a post which is provided at the top, on each of two opposite sides, with level indicating means comprising, in the present instance, a stop block 13 the depth of which is preferably equal to the depth of the panels minus the thickness of the sheet of metal out of which the panels are formed. When the posts are 85 of wood, I prefer to nail the stop blocks in place, but it will be readily understood that any suitable arrangement depending upon the character of the material employed, may be used. A suitable distance below the stop blocks I provide other blocks 14 which are also secured to the posts, the distance between the blocks 13 and 14 being greater than the maximum width of ledgers to be used. The upper surfaces of the blocks 14 are inclined and wedges 15 are carried thereon, such wedges in turn carrying the ledgers 9 and 10. 95

The ledgers may vary considerably in

width and the wedges are utilized to drive the upper edge of the ledgers tightly against the blocks 13 so as to properly fix the level of the ledgers with respect to the top of the shores. Thus the blocks 13 serve not only as fixed level indicators for adjustment of the ledgers 9 to bring their upper edges to the desired height on the shores 7, but also as stops for positively preventing the ledgers 10 from being raised too high, and as securing means for holding the ledgers tightly fast. Thus the floor form sections 11 are separately adjusted relatively to the various shores 7, to adjust and level the sections 15 themselves to the proper height. Each post is provided with a pair of buttons 16 preferably in the form of arms pivoted to the post by means of the bolts 17. When these buttons are swung to horizontal position they will clear the ledgers and these can be removed by loosening or knocking out the wedges 15. When the buttons or arms 16 are in vertical position the upper ends thereof will serve to laterally position the ledgers, 20 cooperating with the shores 7 themselves to prevent accidental displacements. The arms 16 are preferably pivoted nearer to one end than the other so that they will normally occupy a vertical position if the bolts 17 should 25 work too loose.

30 The posts are independently adjusted to the proper floor level or height, less the thickness of the sheet metal plate from which the panels are made, by means of the wedges 35 18 which are carried on the sill 19.

It will be understood that by this arrangement the ledgers are supported so as to be easily taken down, and it is unnecessary to do any fitting for elevation, because the 40 wedges 15 will compensate for any variation in dimension. There are no parts to be taken off; and the only work involved in using the forms is the manual work involved in setting up the parts and driving the wedges to the 45 proper points. One set of form parts can be taken down without interference with adjacent parts; and where a unit arrangement is employed the units may also be taken down without interference.

50 The buttons are sufficiently broad to cover adjacent ends of two stringers, which enables me to use short stringers extending only from shore to shore, if desired.

I claim:

55 1. A shore member for form support and the like having level-indicating means for cooperating directly with another form sustaining falsework member, in combination with means for supporting such falsework member from the shore variable to adjust it to said indicating means.

60 2. A shore member for form support and the like having a level stop for a form sustaining false work member, in combination 65 with means for supporting such false work

member from the shore variable to elevate such false work member into engagement with said stop.

3. A shore member for form support and the like provided with level-indicating 70 means for cooperating directly with a form sustaining falsework member, in combination with means for supporting such falsework member from the shore variable to adjust it to said indicating means, and 75 means cooperating with the shore to prevent displacement of such falsework member from its said supporting means.

4. A shore member for form support and the like provided with a pair of stops spaced 80 apart one above the other to permit of the introduction of a false work form sustaining member between them, in combination with means cooperating with the lower stop for driving such false work member against 85 the upper stop.

5. A shore member for form support and the like provided with a pair of stops spaced apart one above the other to permit of the introduction of a false work form sustaining member between them, in combination 90 with means cooperating with the lower stop for driving such false work member against the upper stop, and a button for preventing displacement of such false-work member. 95

6. A shore member for form support and the like having level-indicating means for cooperating directly with a false work form sustaining member, in combination with means for supporting such false work member from the shore variable to adjust such false work member to said level-indicating means, and means for also adjusting the shore itself, with the parts aforesaid, to the proper height. 100

7. A shore member affording support for a floor form section on its top and having fixed level-indicating means for cooperating directly with a floor form ledger, and means for supporting such ledger from the shore variable to adjust the ledger vertically with reference to said indicating means and bring the upper edge of the ledger to the desired height on the shore. 110

8. The combination of a form section, a 115 false work member for carrying a cooperating form section; a shore for supporting the first-mentioned form section provided with level-indicating means for cooperating directly with said false work member, and means on the shore for supporting said false work member variable to adjust the latter to said level-indicating means, so that both of such form sections shall be supported at the desired level. 120

9. A floor form system comprising a plurality of shores having level indicating means, form sections supported on top of the shores, false work carried by the shores, other form sections supported from the said 130

false work and cooperating with those sections aforesaid to constitute the floor form, means for independently adjusting various shores to the proper heights, so as to support the floor level, and means for separately adjusting the supporting false work of said other form sections against the indicating

means of the various shores, and thereby automatically adjusting and levelling the sections themselves to the proper height. 10

In testimony whereof, I have hereunto signed my name.

LESLIE HOLMES GARLINGHOUSE.
